DESIGN FOR A TEXTILE FABRIC

Charles R. Burns, Reading, Pa., assignor to Vanity
Fair Silk Mills, Reading, Pa., a corporation of
Pennsylvania

Application March 16, 1934, Serial No. 51,081

Term of patent 3½ years

To all whom it may concern:

Be it known that I, CHARLES R. BURNS, a citizen of the United States, residing at Reading in the county of Berks and State of Pennsylvania have invented a new, original, and ornamental Design for a Textile Fabric, as shown in the accompanying drawing, and described in the following specification.

In the drawing:

Figure 1 is a plan view; and

Figure 2 is a similar view on an enlarged scale, showing detail.

The design comprises an arrangement of alternating wide and narrow strips, the edges of the wide strips being delineated by a series of large holes and the wide strips being transversely intersected by rows of smaller holes in line with the large holes, the narrow strips being defined by arcuately arranged meshes lying longitudinally of the strip.

I claim:

The ornamental design for a textile fabric as shown and described.

CHARLES R. BURNS.
